UNITED STATES PATENT OFFICE.

HERBERT E. HAGMUELLER, OF HOBOKEN, NEW JERSEY.

HOOD FOR MOUTHPIECES OF PIPES OR THE LIKE.

1,079,703.

Specification of Letters Patent. Patented Nov. 25, 1913.

Application filed March 27, 1913. Serial No. 757,056.

To all whom it may concern:

Be it known that I, HERBERT E. HAGMUELLER, a subject of the German Emperor, residing at Hoboken, in the county of Hudson and State of New Jersey, have invented certain new and useful Improvements in Hoods for Mouthpieces of Pipes or the like, of which the following is a specification.

The present invention relates to smoking

- 10 pipes or mouthpieces for cigars or cigarettes and more particularly to means for protecting the opening in mouthpieces against clogging and for expelling the nicotine or other matters from the passage of the mouthpiece.
- 15 The device substantially consists of an elastic normally inflated bispherical hood terminating at one end into a narrow nozzle adapted to fit in the opening at the mouthpiece. The hood proper is adapted to be
- 20 turned once over the mouthpiece and then over itself, thereby tightly closing the opening of the mouthpiece and at the same time the air contained in said hood, when the latter is turned or folded over the mouth-
- 25 piece, expels the nicotine or other matters from the passage of the mouthpiece either into the bowl of the pipe or outwardly, in case of mouthpieces for cigars or cigarettes.

An example of my invention is illustrated
30 in the accompanying drawing, which forms a part of this specification and in which similar reference letters denote corresponding parts, Figure 1 showing a pipe partly in section and the hood applied thereto; Fig.
35 2 showing an enlarged longitudinal section of the mouthpiece end of the pipe and of the hood partly drawn or folded over the same; Fig. 3 a similar section of the pipe and of the hood completely drawn over the same and Fig. 4 a longitudinal section of the inflated elastic hood.

a denotes the smoking pipe and *b* the mouthpiece thereof.

The new device consists of an elastic nor-
45 mally inflated bispherical hood *c*, *c'*, the part *c'* being of sufficient diameter to engage around the rounded portion *b'* of the mouth-
piece (Fig. 2) and the part *c* being of some-
what larger diameter so as to be capable of
50 being drawn over the part *c'* (Fig. 3), there
being a contraction between the two parts
c, *c'* (Figs. 1 and 4). The part *c'* termi-

nates into a narrow nozzle *c*², the diameter of which corresponds to that of the passage *b*² of the mouthpiece and is adapted to fit 55 in the said passage (Figs. 1 and 2).

When in use the nozzle *c*² is introduced into the passage *b*² and the part *c'* will be folded or turned over the rounded portion *b'* of the mouthpiece (Fig. 2) and then the 60 part *c* will be turned over the part *c'* (Fig. 3). By the folding of the hood the air contained therein will be pressed into the passage *b*² of the mouthpiece and expel or blow any foreign matter contained therein into 65 the bowl portion of the pipe or outwardly when a mouthpiece for cigars or cigarettes is used. Thus the hood serves a double purpose, namely, first to tightly close the opening of the mouthpiece to prevent it from becoming clogged, when it is carried in one's 70 pocket for instance, and furthermore, as means for automatically expelling or blowing out the nicotine or other matters contained in the passage. 75

What I claim and desire to secure by Letters Patent is:

1. The combination with a mouthpiece of a pipe or the like, of an elastic normally inflated hood having a nozzle at one end, said 80 nozzle being adapted to fit in the opening of the mouthpiece and the hood being adapted to be turned over the mouthpiece and also over itself, so as to protect the opening of the mouthpiece and to expel matters contained in the passage. 85

2. The combination with a mouthpiece of a pipe or the like, of an elastic bispherical inflated hood having a nozzle, said nozzle being adapted to fit in the opening of the 90 mouthpiece, one part of the said hood being adapted to be drawn over the end of the mouthpiece and the second part being adapted to be drawn over the said first part of the hood, whereby the opening of the mouthpiece is tightly closed and the matters contained in the passage of the mouthpiece are 95 expelled or blown out.

In testimony whereof I affix my signature in presence of two witnesses.

HERBERT E. HAGMUELLER.
